J. R. SCHULTZ.
BOTTLE CAP REMOVER.
APPLICATION FILED MAY 8, 1916.

1,219,047.

Patented Mar. 13, 1917.

INVENTOR:
J. R. SCHULTZ,
By *Knight & Cook* Regd.

UNITED STATES PATENT OFFICE.

JOSEPH R. SCHULTZ, OF ST. LOUIS, MISSOURI.

BOTTLE-CAP REMOVER.

1,219,047.

Specification of Letters Patent.

Patented Mar. 13, 1917.

Application filed May 8, 1916. Serial No. 96,201.

To all whom it may concern:

Be it known that I, JOSEPH R. SCHULTZ, a citizen of the United States of America, a resident of the city of St. Louis, State of Missouri, have invented certain new and useful Improvements in Bottle-Cap Removers, of which the following is a full, clear, and exact description, reference being had to the accompanying drawings, forming a part of this specification.

My invention relates to a bottle cap remover and has for its object the production of a simple, efficient, and inexpensive bottle opener which may be readily applied to a counter, a wall, or other suitable support. The preferred form of the invention comprises a circular cap-receiving member provided with means for holding bottle caps, and a flexible retaining device adapted to be bent to secure the cap receiving member to its support.

Figure I is a front elevation of my bottle cap remover.

Fig. II is a rear elevation of the parts shown in Fig. I.

Fig. III is a section taken approximately through the middle of the cap-receiving member.

Fig. IV is a vertical section showing a bottle applied to the bottle cap remover.

A designates a portion of a wall, counter, or other suitable support provided with a circular opening for the reception of my bottle cap remover. B designates a circular bottle cap receiver mounted in the circular opening in the support A and provided at its outer edge with a circular flange 1 adapted to engage the outer face of the support A. 2 designates flexible retaining tongues extending from the inner edge of the cap-receiving member B and adapted to be bent outwardly, as shown in Figs. II and IV to engage the inner face of the support A. It is to be understood that these flexible tongues 2 are adapted to pass through the circular opening before they are bent to the positions shown in the drawings, and that they may be readily bent to coöperate with the flange 1 in securing the cap receiver to the support A.

3 designates an abutment formed interiorly of the cap-receiving member and

adapted to engage the face of the bottle cap, as shown in Fig. IV. An abutment lug 4 extending inwardly from the flange 1 is 55 adapted to engage the crimped edge of the bottle cap. Obviously, the cap may be removed by moving the bottle from the position shown in full lines (Fig. IV) to the position shown by dotted lines.

5 designates sharp lugs extending from the periphery of the circular cap-receiving member and adapted to be embedded in the support A to prevent the cap-receiving member from turning in the circular opening.

The support A may be very easily bored to form the circular opening, and the inexpensive bottle cap receiver may be firmly secured to the support by merely bending the flexible tongues 2.

I claim:

1. A bottle cap remover comprising a circular cap-receiving member, adapted to be mounted in a circular opening in a suitable support, a retaining flange at one edge of 75 said circular cap-receiving member adapted to engage one side of said support, flexible retaining elements extending from the opposite edge of said circular cap-receiving member, an abutment extending inwardly 80 from a point near said retaining flange adapted to be engaged by the edge of the bottle cap, an interior abutment at a point near said flexible retaining elements adapted to be engaged by the outer face of the bottle 85 cap, said flexible retaining elements being so formed that they may be readily inserted through said circular opening and thereafter bent to secure said circular cap-receiving member in said opening, said flange, abutments and flexible retaining elements being 90 formed integral with each other.

2. A bottle cap remover comprising a circular cap-receiving member, adapted to be mounted in a circular opening in a suitable 95 support, a rigid circular retaining flange at the outer edge of said circular cap-receiving member adapted to engage one side of said support, flexible retaining tongues extending from the inner edge of said circular cap-receiving member, an abutment extending inwardly from said circular retaining flange adapted to be engaged by the edge of the bottle cap, an interior abutment member in 100

the form of a reinforcing web formed integral with said circular-cap-receiving member at a point near said flexible retaining tongues, said flexible retaining tongues being so formed that they may be readily inserted through said circular opening and thereafter bent to secure said circular cap-

receiving member in said opening, and sharp ribs 5 extending from the periphery of said circular cap-receiving member to coöperate with said flange and tongues in securing said circular cap-receiving member in said circular opening. 10

JOSEPH R. SCHULTZ.
